(57) **CLAIM**

The ornamental design for a zip seal trash bag, as shown and described.

DESCRIPTION

FIG. 1 is a front, top perspective view of the first embodiment of the zip seal trash bag in a partially open condition showing my new design;

FIG. 2 is a plan view thereof;

FIG. 3 is a rear plan view thereof;

FIG. 4 is a right side view, the left side view being a mirror image thereof;

FIG. 5 is a top view thereof;

FIG. 6 is a bottom view thereof;

FIG. 7 is a front, top perspective view of the second embodiment of the zip seal trash bag;

FIG. 8 is front plan view thereof;

FIG. 9 is a rear plan view thereof;

FIG. 10 is a front, top perspective view of the third embodiment of the zip seal trash bag;

FIG. 11 is a front plan view thereof; and,

FIG. 12 is a rear plan view thereof.

FIGS. 4, 5 and 6 are also the right/left side, top and bottom views of the second and third embodiments of the zip seal trash bag.
